UNITED STATES PATENT OFFICE.

CHAUNCEY M. GOODRICH, OF THE UNITED STATES ARMY.

KNOCKDOWN BUILDING.

1,350,493.

Specification of Letters Patent. Patented Aug. 24, 1920.

Application filed November 13, 1918. Serial No. 262,385.

(FILED UNDER THE ACT OF MARCH 3, 1883, 22 STAT. L., 625.)

To all whom it may concern:

Be it known that I, CHAUNCEY M. GOODRICH, major of engineers, U. S. Army, a citizen of the United States, stationed at Washington, D. C., have invented an Improvement in Knockdown Buildings, of which the following is a specification.

The invention described herein may be used by the Government, or any of its officers or employees in prosecution of work for the Government, or by any other person in the United States, without payment of any royalty thereon.

This invention relates to improvements in buildings of the knockdown, or ready to erect class in which the parts are constructed in multiple and adapted to be transported in crates, boxes or bundles to the locality where the building is to be erected and there assembled.

The principal object of the present invention is to improve and simplify the construction, decrease the time and labor required to erect the building, and increase the efficiency and utility of the same.

Another object of the invention is to provide a structure of this character which may be rendered completely sanitary for use as a hospital without material structural change.

Another object of the invention is to provide a structure of this character formed in sections so that the length may be increased or decreased by adding or detaching sections.

With these and other objects in view the invention consists in certain new and useful improvements hereinafter described and specifically set forth in the claims, and in the drawings illustrative of the preferred embodiment of the invention—

Figure 1 is a transverse section of the improved structure.

Fig. 2 is a sectional detail illustrating the construction of the floor and side walls.

Fig. 3 is a perspective view of the shoe for supporting the floor joist and the side and roof supports.

Fig. 4 is a view of the blank from which the shoe is constructed.

Figs. 5, 6 and 7 are sectional details illustrating the manner of fastening the purlin

members, the roof covering and the inner wall or ceiling members in position.

Fig. 8 is a detail side view of portions of the wall and ceiling members and a portion 55 of one of the joining strips, illustrating the manner of uniting and supporting the confronting horizontal edges.

Fig. 9 is a section on the line 9—9 of Fig. 8.

Figs. 10 and 11 are cross-sectional detail views.

The improved structure comprises in general longitudinally directed sill members in sections, joist members in sections and bearing at their ends upon the sills, side and roof supports in sections and preferably semicircular in outline, a plurality of purlin members in sections and extending transversely of the wall and roof supports, wall and roof 65 sections engaging over the wall and roof supports, and a ceiling in sections and bearing upon the inner faces of the wall and roof supports.

The sill members are represented at 10 and 75 extend longitudinally of the building at each side. Where the building is relatively short the sill members will each be in one piece, but for longer buildings the sill members will be in sections abutting end to end 80 and the ends coupled by suitable means.

The joists are represented at 12 and bear at their ends over the inner portions of the sills, as shown.

If the buildings are relatively narrow, the 85 joists will each be in a single piece, but for wider buildings each joist will be in two or more sections abutting end to end with channel shaped coupling members 13 engaging and supporting the adjacent ends and secured thereto by bolts or rivets or other fastening devices. The coupling members will be further supported by blocks bearing upon the ground, if required.

The walls and roof supports are represented at 14 and formed of L bars arranged in pairs with the confronting webs at spaced intervals.

When the side walls and roof are semicircular in outline the supports 14 are correspondingly curved as shown in Fig. 1, and in relatively large buildings the members 14 100

will be in a plurality of sections abutting end to end and the ends coupled by sections of L bars 15 bolted, riveted, or otherwise connected over the confronting terminals. 5 Spacing washers 14³ are preferably arranged around the fastening devices between the confronting webs of the members 14 to maintain them in spaced relation. Tie rods 14' are disposed transversely through the 10 outstanding webs of the members 14, the webs being separated by spacer washers 14² where the rods pass through. If preferred the tie rods may be extended through all of the outstanding webs at each side of the 15 building.

Bearing upon the sill members and extending beneath each of the ends of the joists is a shoe device formed initially as 20 shown in Figs. 3 and 4 of a plate of sheet metal including a central body portion 16 with clefts 17 whereby wings 18 are released at one side of the clefts and adapted to be bent at right angles to the body portion, the joist bearing upon the central or intermediate 25 part 16 and the wings 18 bearing upon opposite sides of the joist. The portion of the plate at the opposite side of the clefts is formed with an intermediate recess 19 and the parts of the plate at opposite sides 30 of the recess bent at right angles to the plate to form wings 20. The lower ends of the lateral webs of the supporting members 14 are seated in the spaces between the wings 20 and 18 while the outstanding webs are 35 located in the recess 19.

The bearing plates with their wings 18 and 20 form "shoes" or supports for the joist and the supporting members to effectively couple the joist and the supporting 40 members to the sill.

The floor of the building rests upon the joists 12, but as the specific construction of the floor is the subject matter of a separate application it is not further described. The 45 floor will preferably be in sections corresponding in width to the wall sections.

The supporting members 14 will generally be spaced about 4 feet from center to center, and to facilitate the assembling of the units 50 which form the completed structure, the floor sections will preferably correspond in width to the spaces between the members 14.

Attached to the inner faces of the supports 14 is a ceiling or inner covering, preferably formed of sections 25 of laminated or "wall board" material. The sections of wall material will generally correspond in width to the spaces between the members 14 so that the joints between the wall sections 60 are located opposite the centers of the supports 14.

At their corners and at suitable intervals along the edges, the wall sections 25 are provided with recesses to receive clamp bolts 65 27, and bearing over the joints between the

wall sections are binder strips 28. The bolts 27 are headed at their outer ends as shown at 27' to bear upon the webs 14, and extend at their inner ends through the binder strips 28 and threaded to receive clamp nuts 27'. 70

By this means the ceiling and wall members are secured in position and may be detached without disturbing the other portions of the structure.

Engaging transversely of the supports 14 75 are purlin members 29 spaced at suitable intervals, as shown.

Clamp bolts are extended through the strips 28 and thence between the spaced webs of the members 14, and provided with 80 heads 31 bearing upon the webs of the members 14 and threaded at their inner ends to receive binding nuts 32 which engage the adjacent faces of the strips. By this means the wall and ceiling supports and the inner 85 wall or cover sections are firmly connected and supported with one set of the bolts.

The roof portion of the improved structure is formed of plates 33 of corrugated sheet metal overlapping at their sides and 90 ends and bearing upon the purlins 29 at their overlapping parts, and at intermediate points, if required.

The roof plates are coupled to the purlins by hook bolts 34 extending through the 95 overlapping portions of the plates and engaging the purlins by their hooked ends, and secured in position by clamp nuts 34' bearing upon the roof members, as shown.

By the arrangement of parts shown the 100 roof plates may be independently connected to the purlins and may be independently attached or detached without disturbing other portions of the structure.

The improved building is provided with 105 suitable closures for the ends, not shown as they form no part of the present invention.

As before stated the wall and ceiling supports 14, the roof section 33, the wall and ceiling members 25, and the floor sections 110 21, are preferably of uniform width, so that the length of the building may be increased practically to an unlimited extent by simply multiplying the sections. Thus, given a plurality of the wall and floor sections and 115 two sets of the end sections, a building of any required length may be quickly erected and the parts as quickly disconnected, when required.

In the higher class of buildings, or those 120 in which a plurality of the wall members 25 are required for each frame section, their contiguous ends will be coupled by grooved or channeled strips 46, as shown in Figs. 8 and 9.

Having thus described the invention what is desired to secure by Letters Patent is:

1. A knock down building, including joists, supports, and a connecting member for securing the supports to the joists com- 130

prising a body portion, wings extending along the longitudinal edges of the body portion and bent at right angles thereto to form a socket for the reception of the end 5 of a joist and spaced apart wings at one end of the body portion bent at right angles thereto and spaced from the first mentioned wings and lying in a plane at right angles to the planes of said first wings and forming 10 a socket for the reception of the end of the supports.

2. A knock down building, including joists, supports, consisting of angle bars arranged in pairs and joined together along

adjacent flanges to form substantially a T- 15 beam, and a connecting member comprising a body portion, wings formed along the longitudinal edges of the body portion and bent at right angles thereto to form with the body portion a socket for the reception 20 of an end of the joist and wings formed at one end of the body portion and bent at right angles thereto, said wings spaced from the first mentioned wings to provide a space 25 for the reception of the flanges of the supports.

CHAUNCEY M. GOODRICH.
